UNITED STATES PATENT OFFICE.

ALOYSIUS C. LIPPERT, OF KENOSHA, WISCONSIN, ASSIGNOR OF ONE-HALF TO C. A. NORTON, OF CHICAGO, ILLINOIS.

RADIATOR-CAP-LATCHING DEVICE.

Application filed February 13, 1925. Serial No. 8,944.

This invention relates in general to radiator caps, and more particularly to a radiator cap adapted to be secured to a radiator neck having a filling opening and a hinged closure therefor.

The principal object is to provide such a device that will be efficient, readily operable and in which the possibility of breakage by accidental opening of the closure is eliminated.

Another important object is to provide such a device that may be economically manufactured, in that few and relatively simple parts are required and that these parts may be readily assembled.

Numerous other objects and advantages will be apparent as the invention is better understood from the following description, which, taken in connection with the accompanying drawings, discloses a preferred embodiment thereof.

Referring to the drawings:

Fig. 1 is an elevation of a device embodying my invention;

Fig. 2 is a plan view thereof;

Fig. 3 is a section taken substantially on line 3—3 of Fig. 2; and

Fig. 4 is a section taken substantially on line 4—4 of Fig. 2.

To illustrate my invention, I have shown a body 11 having an opening 12 therethrough. An annular flange 13 in the top of the opening 12 provides a seat for a gasket 14. The body 11 may be secured to a radiator neck by any suitable means such as by an insert or locking device to prevent removal of the cap. In the present instance, I have shown the diameter of the opening 12 enlarged at the lower end and threaded at 15 by which the body may be secured to the neck of a radiator 16.

The body 11 is provided with oppositely disposed outwardly extending arms 17 which may be of any desired shape having a suitable base 18. Recesses 19 and 21 are provided in the body 11, preferably at the base of the arms 17. A closure member 22 apertured at 23 to receive a condition indicator or motor meter 24 is provided to close the opening 12 and is pivoted to the body by means of a hinge pin 25 extending through a hinge lug 26 formed integral with the closure member and having bearings in the body at each side of the hinge lug. While it is possible to hinge the closure member 22

at any point alongside the opening 12, to protect the hinge against damage or unauthorized removal and to aid in the symmetrical appearance of the device, I prefer to conceal the hinge by extending the lug 26 into the recess 19 and below the top plane of the body. It will be noted that the hole into which the hinge pin 25 is driven does not extend clear through the cap and that to remove the pin it will be necessary to complete the hole from the opposite side to permit driving out of the pin and removal of the cover mechanism.

A latch is provided for latching the closure member in closed position or against the gasket 14, preferably opposite the hinge, and in the recess 21 in an arm 17 as will now be described.

A latch 27 having an operating arm 28 which is preferably formed in accordance with the contour of an arm 17 and cam lugs 29, is pivoted to a link 31 by a pin 32. The link 31 is pivoted to the body 11 by means of an anchor pin 33 driven into a shallow hole in the body to prevent removal. Cam lugs 29 are adapted to engage over the lugs 34 formed integral with and as a part of the closure member 22, the lugs 34 being spaced apart to provide a channel 35 through which the link 31 may extend when the latch is in closed position (Fig. 3).

It will be noted that the cam lugs 29 of the latch 27 have a long and a short diameter, and that when the long diameter is in engagement with the lugs 34, the closure member is tightly pressed against the gasket 14 and that upon movement of the operating arm 28 in a counter-clockwise direction to the extent of approximately 90 degrees, the long diameter of the lugs 29 will be withdrawn from engagement with the lugs 34. The short diameter of the lugs 29 not being sufficiently long to engage the lugs 34 permits the swinging of the latching mechanism about the anchor pin 33 and out of engagement with the lugs 34 which entirely releases the closure member and permits opening thereof for filling the radiator. Upon closing the closure member, the above described operations are reversed to latch the closure in closed position. It will be noted that the link 31 and the cam lugs 29 form a toggle and a very tight closure may be effected thereby, and that all parts of the latching mechanism are substantially con-

sealed eliminating the possibility of accidental or unintentional opening of the closure member or destruction of the parts.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

15 I claim:

1. A radiator cap, comprising a body adapted to be secured to a radiator neck and having a filling opening therethrough, a closure member pivotally secured to said body for closing said opening, and a latching mechanism for securing said closure member in closed position comprising an anchor pin secured to the body, a link pivoted to said anchor pin and a latch secured to said link having a cam face adapted to engage a portion of said closure member and a handle to facilitate operation the cap body being recessed to receive the latching elements and the interengaging parts of the latter being substantially concealed within the body.
2. A radiator cap, comprising a body adapted to be secured to a radiator neck having a filling opening therethrough and a portion extending outwardly therefrom, a closure member for said opening pivotally secured to said body for closing said opening, and a latching mechanism for securing said closure member in closed position comprising an anchor pin secured to the body, a link pivoted to said anchor pin, and a latch secured to said link having a plurality

of cam faces adapted to engage a portion of said closure member and a handle to facilitate operation, said handle being formed to embrace the outwardly extending portion of said body when in latched position.

3. A radiator cap, comprising a body adapted to be secured to a radiator neck having a filling opening therethrough and a plurality of outwardly extending arms having recesses therein at their base, a closure member for said filling opening having a hinge lug adapted to extend into a recess in one of said arms and a latching portion extending into a recess in an opposite arm, a hinge pin, and means for latching said cover in closed position comprising an anchor pin secured to the body, a link pivoted to said anchor pin, and a latch for engaging a portion of the closure member having a handle to facilitate operation, said handle being formed to embrace the outwardly extending portion of said body when in latched position.

4. A radiator cap, comprising a body adapted to be secured to a radiator neck having a filling opening therethrough and a plurality of outwardly extending arms provided with recesses, a closure member for said filling opening having a hinge lug adapted to extend into a recess in one of said arms and a latching portion extending into a recess in an opposite arm, a hinge pin, and means for latching said cover in closed position comprising an anchor pin secured to the body, a link pivoted to said anchor pin, and a latch engaging a portion of the closure member having a handle to facilitate operation, said handle being formed in accordance with the contour of an outwardly extending arm.

ALOYSIUS C. LIPPERT.
